Madison Shipman Inventor

UNITED STATES PATENT OFFICE.

MADISON D. SHIPMAN, OF DE KALB, ILLINOIS.

DESIGN FOR A BUTTON.

SPECIFICATION forming part of Design No. 32,722, dated May 29, 1900.

Application filed May 1, 1900. Serial No. 15,137. Term of patent 14 years.

To all whom it may concern:

Be it known that I, MADISON D. SHIPMAN, a citizen of the United States, residing at De Kalb, in the county of De Kalb and State of Illinois, have invented and produced a new and original Design for Buttons; and I do declare the following to be a full, clear, and exact description of the same, reference being had to the accompanying drawings, forming 10 a part thereof.

My present invention relates to new and original designs in buttons.

In the accompanying drawings, which form a part of this specification, Figure 1 is a plan 15 view of a button, showing my new design. Fig. 2 is an edge view of the same.

As shown in the drawings, my design consists of a series of shell-like figures having circinate inner ends, which form a central

20 polygonal figure. The shell-like figures extend outward toward the outer edge of the button, and within their enlarged portions a circle is formed. In the spaces between the curved outer ends of the shell-like figures are small angular figures, each provided with a 25 ring.

The essential feature of this design is the central polygonal figure encircled by the outlying series of shell-like figures.

Having thus fully described my invention, 30 what I claim is—

The design for a button, substantially as shown and described.

MADISON D. SHIPMAN.
